CLOSURE FOR DETENTION WINDOW-
GUARD ASSEMBLIES

William D. Bayley, Springfield, Ohio, assignor to
The William Bayley Company, Springfield,
Ohio, a corporation of Ohio

Application November 4, 1935, Serial No. 48,176

10 Claims. (Cl. 189—64)

This invention relates to detention windows and in more particular to a detention window assembly wherein the conventional guards, having detention bars supported in fixed relation by a plurality of rail bars, form the support for the glass either directly or indirectly.

An object of this invention is to produce a window that is cheap, easily constructed, very efficient in preventing the escape of human bodies through the window and at the same time presenting a neat appearance.

Another object of this invention is to provide glass supporting members interlocking with the guards to permit easy construction of the window assembly, resulting in a substantial permanent structure.

Another object of this invention is to provide supporting members for the glazing transversely arranged with respect to the glass supporting 20 muntins, concealing detention bars.

Another object of this invention is to provide a removably mounted member cooperating with other glass supporting member to hold the glazing in position.

Another object of this invention is to provide a closure for the ventilating area found in the guard window assembly, the closure being separated from the metallic parts of the guard except for the necessary connection which may be accomplished by placing mounting means intermediate the guard and the closure.

Another object of this invention is to space the parts of the window structure from the guard as far as possible to prevent corrosion.

With the above primary and other incidental objects in view, as will more fully appear in the specification, the invention consists of the features of construction, the parts and combinations thereof, and the mode of operation or their equivalents, as hereinafter described and set forth in the claims.

Fig. 1 is a front elevation of the window assembly.

Fig. 2 is a vertical sectional view taken substantially on the line 2—2 of Fig. 1.

Fig. 3 is a horizontal sectional view taken substantially on the line 3—3 of Figs. 1 and 2.

Fig. 4 is a vertical sectional view of another modification wherein the closure assembly is mounted on the side of the detention bars opposite the glazing.

Fig. 5 is a horizontal sectional view taken substantially on line 5—5 of Fig. 4.

This application is related to my copending application Serial No. 687,323 filed August 29, 1933,

Patent No. 2,020,046, granted Nov. 5, 1935. In my copending application the glazing extended across the entire window assembly. The glazing is supported upon members extending parallel to the rail bars of the guards. In the present embodiment the window supporting members extend parallel to the detention bars, so as to conceal the same, except across the ventilating area. The glass supporting members aligned with the detention bars are preferably T-shaped, having the flanges notched, so as to fit over the edges of the rails, thereby holding the glass supporting members in a rigid, compact relation with respect to the guards, the stem of the T-shaped bars extending between the window panes. Adjacent to the ventilating area of the stems of the T-bars have preferably been notched, so as to accommodate the glass supporting members bounding the ventilating area.

Referring to the drawings the detention bars 10, having the opposite ends embedded in the masonry bounding the ventilating area, are held in spaced relation by a plurality of parallel rail bars 12, also having their ends embedded in the masonry. Although the rail bars and detention bars have been shown as embedded in the wall surrounding the window opening, the detention bars and rail bars may be otherwise held in position. In the modification disclosed the detention bars are passed through holes provided therefor in the rail bars. The detention bars 10 may be provided with ribs 14, for interlocking the rails in position, as is well known to those skilled in the art.

The glazing 16 extending over a portion of the guard, is supported upon T-bars 18, having their flanges notched at 20, so as to fit over the margin of the rail bars. The T-bars 18 are preferably aligned with respect to some of the detention bars, so as to conceal the same, thereby eliminating the objectionable appearance of these detention bars. The stems 22 of the T-bars 18 separate the window panes. The stems are preferably notched at 24 and 26, so as to accommodate the transversely arranged glass supporting members 28 and 29, respectively.

The glass supporting member 28 shown in Fig. 2 is a portion of the frame of the closure assembly 30 extending over the ventilating area. The T-bars 18, which constitute muntin bars for the fixed glazing and the closure 30, are held in position by members 32, having holes receiving the detention bars 10 and suitable flanges 34 that are suitably secured in position. Thus, it will be seen that the T-bars or muntin bars 18 interlocking

the rail bars 12, which are seated in the notches 20 and the closure frame 30, are held in a rigid unitary structure by members 32. The glass supporting flanges 28 and the muntin bars 18 form 5 three sides of the glass supporting means. The fourth side of the glazing is held in position by the glazing strips 29, which may be flat bars having holes receiving the studs 36, welded or otherwise attached to the stem 22 of the T-bar 18. 10 The strips 29 may be held in position by nuts 38 threadedly engaging the studs 36.

In the modification disclosed in Figs. 1, 2, and 3, the closure 30 for the ventilating area has been mounted on the same side of the detention bars 15 as the glazing 16. Referring to Figs. 4 and 5 the closure assembly 30 has been mounted on the side of the detention bars opposite the glazing 16. The closure may be attached to the detention bars 10 in any suitable manner for example, the retaining members 32 as shown in Fig. 4. In this 20 modification angle bar 40, having the flange 42 secured to the structure and the flange 44, is arranged to form a seat for the glazing 16. The space intermediate the muntin bars bounding the 25 ventilating area and closure frame disposed in the opposite side of the detention bars may be closed in any suitable manner, as by a metallic member 31.

In each of these modifications the glazing 16 30 extending along the bottom or the sill of the window is preferably held in position by putty, providing water-tightness between the lower rail 12 and the masonry surrounding the window. In order to prevent water coming in at the closure, 35 water-shedding members 46 and 48 respectively are provided adjacent to the closure in any suitable manner.

In the modification shown in Fig. 4 a screen 50 is mounted in aligned relation with the glazing 40 16. The screen includes a frame 52 suitably attached to the window assembly.

In view of the fact that it may oftentimes be desirable to have a closure for the ventilating area that is higher than the distance between the two 45 adjacent rails 12 in the normal guard assembly, one or more of the rails 12 may be omitted across the ventilating area and rail bars 54 of a different cross sectional area, preferably welded to the detention bars 10, may be used to support the 50 detention bars in a fixed spaced relation. The rail bars 54 may be spaced closer so as to give additional protection to the more vulnerable areas of the window assembly. These bars 54 may be mounted upon the side opposite the closure, so 55 that when the closure is mounted upon the same side of the detention bars as the glazing 16, the rail bars 54 will be mounted upon the opposite side of the detention bars. If the closure is mounted upon the opposite side of the detention 60 bars from the glazing 16, the rail bars are preferably mounted upon the same side as the glazing. The spacing of the glazing 16 and the closure 30 from the rail bars and the detention bars permits washing of the glazing, both in the free areas and 65 the areas intermediate the glass and the detention and rail bars. This has been found to be a very desirable feature.

In all of the above modifications the metallic parts subject to corrosion are separated as far as 70 consistent with the utility. The spaces intermediate adjacent metallic parts are, wherever feasible, sealed with putty or other suitable sealing material. Where this is not done, it has been found very difficult to prevent adjacent metallic members from rusting, as it is almost impossible 75

to paint the metallic joints so as to provide permanent water-tightness. Putty is preferably put into the vertical and horizontal spaces between the closure frame and rail bars 12. The horizontal space between the closure frame and the 5 adjacent rail bar 12 may be spaced sufficiently far apart to permit painting of the rail bars and the closure frame in which event putty is omitted. Putty has been found far more suitable. The guard, the muntin bars and the closure may have 10 the exposed portions painted, the parts being so constructed and arranged as to permit the separation of the parts by paint or sealing the junction to eliminate rusting.

Although the T-bars have been shown with 15 notches the T-bars may extend continuously across the guard either in off-set relationship or seated in seats provided therefor in the guard assembly.

The glazing may be mounted on either the outside or the inside of the glazing depending entirely upon the demands.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any 30 of its advantages.

While in order to comply with the statute, the invention has been described in language more or less specific as to structural features, it is to be understood that the invention is not limited 35 to the specific features shown, but that the means and construction herein disclosed comprise the preferred form of several modes of putting the invention into effect, and the invention is therefore claimed in any of its forms or modifications 40 within the legitimate and valid scope of the appended claims.

Having thus described my invention, I claim:

1. A window supported upon a detention guard having a plurality of parallel detention bars supported in fixed relation by transversely arranged rail bars, said window including a plurality of parallel T-shaped muntin bars arranged in aligned relation with respect to the detention bars to conceal the same, at least one of said 50 muntin bars terminating at a ventilating area of the window, the T-bars having the flanges notched in which notches the margins of the rail bars are positioned, the stem of the T being notched adjacent one end, an angle bar extending 55 along the side of the closure having a flange projecting into the notch in the end of the stem of the T-bar and a closure assembly positioned on the side of the detention bars opposite the muntin bars. 60

2. A sash assembly including detention means having a plurality of detention bars held in spaced relation by a plurality of rail bars, dividing the window into a plurality of spaces, some of which are glazed by window panes extending along one side of the detention bars leaving at least one space vacant for ventilating area, a closure assembly for the ventilating area, said closure assembly being mounted on the side of the detention bars opposite said glazing, and means linking the detention bars for supporting the closure assembly. 65

3. A window assembly including a detention guard having a set of parallel detention bars held in spaced relation by a set of rail bars divid- 70

- ing the window into a plurality of spaces, some of which form a ventilating area, muntin bars for supporting the glazing on one side of the detention bars, said muntin bars extending parallel to one set of bars and arranged to interengage the other set of bars, and a closure assembly for the ventilating area mounted on the side of the detention bars opposite the muntin bars.
5. A detention window assembly including a detention guard having a plurality of parallel detention bars held in fixed spaced relation by a plurality of rail bars transversely disposed with respect to the detention bars, means extending parallel to the detention bars for supporting the glazing of the glazed spaces, said means being offset from the detention bars, a closure for an unglazed space left vacant for ventilation, said closure being mounted on the side of the detention bars opposite the glazing, and means spanning the space intermediate the closure and said first means for providing weather tightness.
10. A window assembly including a detention guard having a plurality of parallel detention bars held in fixed spaced relation by a plurality of transversely arranged rail bars, muntin bars for supporting the glazing extending parallel to one set of bars, a closure having a frame bounding a ventilating area over which the detention bars extend and auxiliary detention bars extending across the ventilating area in transverse relation to the first mentioned detention bars and welded thereto to provide additional protection over the more vulnerable area of the window.
15. A window assembly including a detention guard having a plurality of parallel detention bars held in fixed spaced relation by a plurality of rail bars dividing the window into a plurality of spaces, some of which form a ventilating area, muntin bars for supporting the glazing, said muntin bars extending parallel to the detention bars, a closure for the ventilating area and auxiliary detention bars extending across the ventilating area in transverse relation to the first mentioned detention bars and attached thereto to provide additional protection over the more vulnerable area.
20. A window assembly including a detention guard having a plurality of parallel detention bars held in fixed spaced relation by a plurality of rail bars dividing the window into a plurality of spaces wider than the distance between the detention bars and longer than the distance between the rail bars so as to cause the glazing to extend over both detention bars and rail bars and detention means carried by the detention bars to protect the more vulnerable area of the window.
25. A window assembly including a detention guard having a plurality of parallel detention bars held in fixed spaced relation by a plurality of rail bars dividing the window into a plurality of spaces, each of which is wider than the distance between adjacent detention bars, the wall bounding the window being provided with a glazing channel into which the glazing for the space next to the wall projects and is held in position by putty and additional detention bars extending transversely across the detention bars across the more vulnerable spaces.
30. A window assembly including a detention guard having a plurality of parallel detention bars vertically disposed and held in fixed spaced relation by a plurality of horizontally disposed rail bars said window having portions more vulnerable than other portions thereof, muntin bars extending parallel to some of the detention bars dividing the window into a plurality of spaces, each of which is wider than the distance between two adjacent detention bars, the masonry along the sill of the window being provided with a glazing seat whereby the glazing in at least some of said spaces is supported by the sill of the window, the weight carrying edge of the glazing being surrounded by putty and additional detention means carried by the detention bars to protect the more vulnerable portions of the window.
35. A window assembly including a detention guard having a plurality of parallel detention bars vertically disposed and held in fixed spaced relation by a plurality of horizontally disposed rail bars, muntin bars extending parallel to some of the detention bars throughout the entire length thereof dividing the window into a plurality of spaces, some of which extend along the entire height of the window, said spaces being wider than the distance between two adjacent detention bars, and supports along the top and the bottom of the window cooperating with the muntin bars for supporting the glazing extending uninterruptedly from the top to the bottom of the window so as to cause the glazing to extend over both detention bars and rail bars.
40. A window assembly including a detention guard having a plurality of parallel detention bars vertically disposed and held in fixed spaced relation by a plurality of horizontally disposed rail bars, muntin bars extending parallel to some of the detention bars throughout the entire length thereof dividing the window into a plurality of spaces, some of which extend along the entire height of the window, said spaces being wider than the distance between two adjacent detention bars, and supports along the top and the bottom of the window cooperating with the muntin bars for supporting the glazing extending uninterruptedly from the top to the bottom of the window so as to cause the glazing to extend over both detention bars and rail bars.
45. A window assembly including a detention guard having a plurality of parallel detention bars vertically disposed and held in fixed spaced relation by a plurality of horizontally disposed rail bars, muntin bars extending parallel to some of the detention bars throughout the entire length thereof dividing the window into a plurality of spaces, some of which extend along the entire height of the window, said spaces being wider than the distance between two adjacent detention bars, and supports along the top and the bottom of the window cooperating with the muntin bars for supporting the glazing extending uninterruptedly from the top to the bottom of the window so as to cause the glazing to extend over both detention bars and rail bars.
50. A window assembly including a detention guard having a plurality of parallel detention bars vertically disposed and held in fixed spaced relation by a plurality of horizontally disposed rail bars, muntin bars extending parallel to some of the detention bars throughout the entire length thereof dividing the window into a plurality of spaces, some of which extend along the entire height of the window, said spaces being wider than the distance between two adjacent detention bars, and supports along the top and the bottom of the window cooperating with the muntin bars for supporting the glazing extending uninterruptedly from the top to the bottom of the window so as to cause the glazing to extend over both detention bars and rail bars.
55. A window assembly including a detention guard having a plurality of parallel detention bars vertically disposed and held in fixed spaced relation by a plurality of horizontally disposed rail bars, muntin bars extending parallel to some of the detention bars throughout the entire length thereof dividing the window into a plurality of spaces, some of which extend along the entire height of the window, said spaces being wider than the distance between two adjacent detention bars, and supports along the top and the bottom of the window cooperating with the muntin bars for supporting the glazing extending uninterruptedly from the top to the bottom of the window so as to cause the glazing to extend over both detention bars and rail bars.

WILLIAM D. BAYLEY.
